UNITED STATES PATENT OFFICE

ALEXANDER E. THOMAS, OF NEW YORK, N. Y.

DESIGN FOR A FOUNTAIN PEN HOLDER DESK STAND

Application filed February 11, 1932. Serial No. 42,816. Term of patent 3½ years.

To all whom it may concern:

Be it known that I, ALEXANDER E. THOMAS, a citizen of the United States, residing at New York, in the county of New York and State of New York, have invented a new, original, and ornamental Design for a Fountain Pen Holder Desk Stand, of which the following is a specification, reference being had to the accompanying drawings forming part thereof,

Fig. 1 is a top plan view of a fountain pen holder desk stand, showing my new design.

Fig. 2 is a front elevational view of the same.

I claim:

The ornamental design for a fountain pen holder desk stand, as shown.

In testimony whereof I have affixed my signature.

ALEXANDER E. THOMAS.
